US0D1086557S

(12) **United States Design Patent** (10) **Patent No.:** **US D1,086,557 S**
(45) **Date of Patent:** **** Jul. 29, 2025**

(54) **DISPOSABLE COSMETIC CONTAINER**

(71) Applicant: **AMOREPACIFIC CORPORATION**,
Seoul (KR)

(72) Inventor: **Jihyun Kim**, Seoul (KR)

(73) Assignee: **AMOREPACIFIC CORPORATION**,
Seoul (KR)

(***) Term: **15 Years**

(21) Appl. No.: **29/885,609**

(22) Filed: **Feb. 27, 2023**

(30) **Foreign Application Priority Data**

Aug. 31, 2022 (KR) 30-2022-0035568

(51) **LOC (15) Cl.** **28-02**

(52) **U.S. Cl.**

USPC **D28/5**

(58) **Field of Classification Search**

USPC D28/4, 5, 6, 7, 8.1, 9, 73, 76, 85, 88;
D9/425, 651

CPC A45D 40/00; A45D 40/023; A45D 33/00;
A45D 37/00; A45D 34/00
